ABSTRACT

An aftermarket accessory in the form of an ergonomic grip for a mobile electronic device. The ergonomic grip includes a grip element hingedly coupled to a planar plate. The grip element includes a plurality of integrally molded annular loops forming a plurality of finger through holes. The ergonomic grip is attached superjacent the verso surface of a mobile electronic device or mobile electronic device cover via a suitable adhesive.

ERGONOMIC GRIP FOR A MOBILE ELECTRONIC DEVICE

I. RELATED APPLICATIONS

The present application is a Continuation-in-Part of U.S. Non-provisional patent application Ser. No. 17/549,050, filed on Dec. 13, 2021, which claims priority to U.S. Provisional Patent Application No. 63/138,658, filed on Jan. 18, 2021, wherein the disclosures both of which incorporated herein by this reference in their entireties.

II. FIELD OF THE INVENTION

The present application discloses and describes an after-market accessory in the form of an ergonomic grip for a mobile electronic device, such as a smart phone.

III. MOTIVATION OF THE INVENTOR

Presently, the prior art discloses devices for protecting mobile electronic devices against damage and devices for enhancing grasp and grip thereof.

A search of the prior art did not disclose any patents that read directly on the claims of the instant invention; however, the following references were considered related:

- U.S. Pat. No. 9,653,934 B2, issued in the name of Forristall et al.;
- U.S. Patent Application No. 2016/0049983 A1, published in the name of Ripka;
- U.S. Pat. No. 10,849,413 B2, issued in the name of Hayes;
- U.S. Pat. No. 9,995,432 B1, issued in the name of Girault;
- U.S. Patent Application No. 2012/0042476, published in the name of Karmatz;
- U.S. Patent No. D883, 268 S, issued in the name of Daniel; and
- U.S. Patent Application No. 2016/0036480 A1, published in the name of Hirsch.

Accordingly, a need continues to exist and is recognized for improvements to aftermarket accessories for mobile electronic devices, such as protective guards and cases, which provide both an enhanced firm hold and grip.

This application presents claims and embodiments that fulfill a need or needs not yet satisfied by the products, inventions and methods previously or presently available. In particular, the claims and embodiments disclosed herein describe an ergonomic grip for a mobile electronic device, the ergonomic grip comprising a planar plate and a grip element, the grip element is hingedly coupled to the planar plate, the grip element comprises a body comprising at least one integrally molded annular loop forming at least one finger through hole, the ergonomic grip providing unanticipated and nonobvious combination of features distinguished from the products, inventions and methods preexisting in the art. The applicant is unaware of any device, apparatus, method, disclosure or reference that discloses the features of the claims and embodiments disclosed herein.

IV. SUMMARY OF THE INVENTION

An aftermarket accessory in the form of a protective cover or case device for a mobile electronic device is disclosed. More particularly, a cover device adapted and configured for protecting electronic smart phone devices is disclosed. According to one embodiment, the protective cover comprises a body having a continuous, peripheral sidewall.

The body includes a grip element rigidly extending integrally, perpendicularly along an outer longitudinal side surface of the peripheral sidewall of the body. The grip element includes one or more loops adjacently aligned and forming a plurality of finger through holes.

According to one embodiment, the grip element may comprise a generally, crescent-shaped configuration.

According to another embodiment, the grip element is designed and configured in the form of a “brass knuckle-type” grip.

In accordance to one embodiment, the body includes one or more distal phalanx braces integrally projecting transversely from the outer surface of the body.

In accordance to another embodiment, the body may further include one or more middle phalanx rests in the form of minor recesses disposed along the outer surface of the body adjacent the continuous, peripheral sidewall supporting the grip element.

In accordance to still another embodiment, a protective case for a portable electronic device, such as a smart phone is disclosed. The protective case comprises a bottom portion and a top portion, the top portion is detachably securable to the bottom portion. The top portion comprises an annular jacket. The bottom portion comprises a generally planar body from which a continuous, peripheral sidewall extends integrally upward therefrom.

The body comprises a grip element rigidly extending integrally, perpendicularly along an outer longitudinal side surface of the continuous, peripheral sidewall of the body.

In accordance to one embodiment, the grip element may comprise a generally, crescent-shaped configuration comprising one or more loops each of which forming finger through holes.

In accordance to another embodiment, the grip element is designed and configured in the form of a “brass knuckle-type” grip.

In accordance to still another embodiment, one or more distal phalanx braces integrally project transversely from the outer surface of the body.

According to another embodiment, the body of the bottom portion may include one or more middle phalanx rests in the form of minor recesses disposed along the outer surface of the body adjacent the continuous, peripheral sidewall supporting the grip element.

According to another embodiment, the grip element is adapted and configured to be detachably secured to the protective cover body or to the body of the bottom portion via a tether and coupling means or other means for facilitating detachable coupling of the grip element to the cover body or the body of the bottom portion.

According to another embodiment, a protective cover for a portable electronic device is disclosed, wherein the cover comprises a generally planar body from which a continuous, peripheral sidewall extends integrally upward therefrom, and a grip element pivotally attached to an outer surface of the body via a pivot means adapted to allow the grip element to be positioned in a flat, compact configuration atop the rear surface of the body.

According to yet another embodiment, an ergonomic grip for a mobile electronic device is disclosed. The ergonomic grip comprises a planar plate and a grip element, the grip element is hingedly coupled to the planar plate. The grip element comprises a plurality of integrally molded annular loops adjacently aligned and forming a plurality of finger through holes. The lower surface of the plate of the ergo-

nomic grip is attached superjacent the verso surface of the smart phone device or smart phone device cover via a suitable adhesive.

V. BRIEF DESCRIPTION OF THE DRAWING(S)

The advantages and features of the present invention will become better understood with reference to the following more detailed description and claims taken in conjunction with the accompanying drawings, in which like elements are identified with like symbols, and in which:

FIG. 1 depicts a top plan view of a protective cover for a portable electronic device, in accordance to one embodiment of the present invention;

FIG. 2 is a bottom plan view of the protective cover of FIG. 1;

FIG. 2A is a bottom plan view of the bottom portion of a protective cover, in accordance to another embodiment of the present invention;

FIG. 3 depicts an exemplary mobile electronic device;

FIG. 4 is a top plan view of the top portion of a protective case for a portable electronic device, in accordance to one embodiment of the present invention;

FIG. 4A is a left side elevational view of the top portion of the protective case of FIG. 4;

FIG. 5 is a top plan view of the bottom portion of a protective case for a portable electronic device, according to one embodiment of the present invention;

FIG. 5A is a bottom plan view of the bottom portion of the protective case of FIG. 5;

FIG. 5B is a left side elevational view of the bottom portion of the protective case of FIGS. 5 and 5A;

FIG. 5C is a top plan view of the bottom portion of a protective case for a portable electronic device illustrating an O-ring disposed about an aperture thereof, in accordance to an alternate embodiment of the present invention;

FIG. 6 is an exploded view showing detachable securing of the top portion to the bottom portion of the protective case, according to one embodiment of the present invention;

FIG. 7 is a cross-sectional view taken along lines VII-VII of FIG. 4, illustrating an O-ring disposed about a window along an interior of the bottom portion of the case, in accordance to one embodiment of the present invention;

FIG. 8 is a top perspective view depicting an ergonomic grip for a mobile electronic device, in accordance to one embodiment of the present invention;

FIG. 8A is a bottom perspective view of a planar plate of the ergonomic grip shown in FIG. 8;

FIG. 8B is a top perspective view of the planar plate in FIG. 8A;

FIG. 8C is a perspective view of a grip element of the ergonomic grip shown in FIG. 8;

FIG. 8D is a perspective view of the ergonomic grip depicting the grip element thereof shown pivotally fixed at an angular orientation of approximately 90°;

FIG. 8E is a perspective view of the ergonomic grip depicting the grip element thereof shown pivotally fixed at an angular orientation of approximately 0°;

FIG. 8F is an end view of an exemplary knuckle having an octagonal cross-sectional shape, in accordance to one embodiment of the present invention; and

FIG. 8G illustrates the ergonomic grip attached to the verso surface of a smart phone device, in accordance to one embodiment of the present invention.

VI. DESCRIPTION OF THE EMBODIMENT(S)

In accordance with FIGS. 1-2, a protective cover for a portable electronic device 10 is disclosed for use with

mobile electronic devices 2 such as mobile phones, tablets, portable media players, personal digital assistants (PDAs), and more particularly for use with mobile electronic smart phone devices 3 such as including, but not limited to, an Apple® iPhone®, a Samsung GALAXY®, and an LG G7®. Conventional, commercially-available smart phone devices 3 include an obverse surface or side 3a opposing a verso surface or side 3b, and a display screen 4 or user-interface screen provided on the obverse side 3a. The protective cover 5 for a portable electronic device 10, hereinafter “cover 10”, is adapted and configured to enclose an entire verso surface and perimeter of a mobile electronic device 2 in a snug-fit, removably-secured manner. For purposes of this disclosure, the terms “snugly” and “snug-fit” are each defined as a substantially-intimate, close-fitting relationship. The cover 10 comprises a generally planar body 12 from which a continuous, peripheral sidewall 13 extends integrally upward therefrom. The sidewall 13 has an upper edge which extends into a slightly incurvate lip 13a. The body 12 includes a front or interior surface 14 and a rear or outer surface 16. The body 12 is adapted with apertures 20 defined therein being shaped, sized, and oriented to accommodate features (e.g., camera lens) of a commercially-available mobile electronic device 2 in a match-fit, positional manner. The body 12 is envisioned to further include button cusps 22 for receiving operational buttons of the mobile electronic device 2, such as the power and volume buttons. Alternatively, it is further envisioned the body 12 may comprise removable panels or cut-out portions (not shown), gains, 15 and/or apertures 20 and button cusps 22. The cut-outs may be scored to facilitate quick, easy, and efficient removal thereof.

The body 12 further comprises a grip element 30 rigidly extending integrally, perpendicularly along an outer longitudinal side surface and outer bottom side surface of the continuous, peripheral sidewall 13 of the body 12. In accordance to one embodiment, the grip element 30 may comprise a generally, crescent-shaped configuration comprising at least one loop 32 forming a finger through hole 34. Preferably, the grip element 30 comprises a plurality of loops 32 adjacently aligned and forming a plurality of finger through holes 34. Most preferably, grip element 30 comprises four loops 32 adjacently aligned and forming four finger through holes 34 sized for receiving user's index finger, middle finger, ring finger, and pinkie; user's thumb remaining free to navigate and operate the interface of the mobile electronic device 2 via the display screen 4 thereof.

In accordance to another embodiment, the grip element 30 is designed and configured in the form of a “brass knuckle-type” grip.

In accordance to one embodiment, the body 12 (including grip element 30) is constructed of a lightweight, rigid or semi-rigid material which may be selected from the group which includes, but is not limited to, thermoplastic olefin composition, polyolefin composition, plastic, thermoplastic, metal or a metallic-plastic composite. Preferred plastic and thermoplastic materials include, but are not limited to, thermoplastic olefin elastomer composition, polystyrene, polyvinyl chloride (PVC), polypropylene, acrylonitrile-butadiene-styrene (ABS), polyethylene, polyurethane, polycarbonate, or blends thereof, and ABS/Nylon blend.

Referring now more particularly to FIG. 2A, in accordance to another embodiment, at least one distal phalanx brace 40 integrally projects transversely from the outer surface 16 of the body 12. Preferably a plurality of distal phalanx braces 40 integrally projects transversely from the outer surface 16 of the body 12. Most preferably, the number

of distal phalanx braces **40** are equal to the number of loops **32**, such as for example, a body **12** comprising four loops **32** and four distal phalanx braces **40**, as depicted in FIG. 2A. Each distal phalanx brace **40** comprises a protruding ridge **42** having a first side and a second side, the ridge **42** terminating upwardly into a curved crest from which the second side of the ridge **42** integrally extends downwardly to a fingertip receiver **44**. The fingertip receiver **44** is a concavity slightly recessed below the outer surface **16** of the body **12**. The crest may be horizontally-oriented, or may be concave-shaped, or convex-shaped.

The grip element **30** and distal phalanx braces **40** combine to provide an ergonomically designed protective cover for a portable electronic device **10** that is uniquely configured to impart user with optimum grip when using the mobile electronic device **2**, such as for example, when taking “selfie” pictures.

Importantly, the protective cover **10** of the present application as designed, shaped, configured and contoured, imparts previously-described functional advantages and features that are unanticipated and nonobvious when compared to the prior art. More specifically, the protective cover **10**, as described herein, is neither anticipated, taught, suggested, nor disclosed by the prior art.

In further reference to FIG. 2A, in accordance with another embodiment, one or more middle phalanx rests **50**, in the form of minor recesses, are disposed along the outer surface **16** of the body **12** adjacent the continuous, peripheral sidewall **13** and lower corner thereof supporting the grip element **30**. Preferably a plurality of middle phalanx rests **50** is disposed along the outer surface **16** of the body **12**. Most preferably, the number of middle phalanx rests **50** is equal to the number of distal phalanx braces **40** and loops **32**. The middle phalanx rests **50** are oriented juxtaposition, respectively, to the finger through holes **34**.

Referring now to FIGS. 4-6, and more particularly FIGS. 4-4A, in accordance to another embodiment, a protective case for a portable electronic device **100** is disclosed for use with mobile devices such as mobile phones, tablets, portable media players, personal digital assistants (PDAs), and more particularly for use with mobile electronic smart phone devices **3** such as including, but not limited to, an Apple® iPhone®, a Samsung GALAXY®, and an LG G7®. The protective case for a portable electronic device **100**, hereinafter “case **100**”, is adapted and configured to enclose an entire verso surface and perimeter of a mobile electronic device **2** in a snug-fit, removably-secured manner. The case **100** comprises a bottom portion **110** and a top portion **160**, the top portion **160** is detachably securable to the bottom portion **110**. The top portion **160** comprises an annular jacket **162** comprising a generally rectangular, incurvate configuration forming a mating receptacle **164** along the rear side thereof, wherein the mating receptacle **164** is adapted for allowing the top and bottom portions **160** and **110** to be detachably secured to one another, and securing the mobile electronic smart phone device **3** mesial the top and bottom portions **160** and **110**. The mating receptacle **164** is configured for receiving and securing the continuous lip **113a** therein via a snap-fit arrangement or mechanical interferential fit.

The top portion **160** further comprises a window **166** defined through a longitudinal side surface and segment of the outer bottom side surface of the jacket **162**. The window **166**, and more particularly the function thereof, shall be described later in greater detail.

Referring now more particularly to FIGS. 4-6, the bottom portion **110** comprises a generally planar body **112** from

which a continuous, peripheral sidewall **113** extends integrally upward therefrom. The sidewall **113** has an upper edge which extends into a slightly incurvate, continuous lip **113a**. The body **112** includes a front interior surface **114** and a rear outer surface **116**. The body **112** is adapted with one or more apertures **120** defined therein being shaped, sized, and oriented to accommodate features (e.g., camera lens) of a commercially-available mobile electronic device **2** in a size-fit, shape, and positional matched manner. In particular reference to FIG. 5C, an annular membrane **122** is disposed along the continuous inner lip edge **121** of the aperture **120** on the front interior surface **114** of the body **112** of the bottom portion **110**. The annular membrane **122**, such as an O-ring **124**, provides a water-impermeable seal about aperture **120** so as to protect the camera lens when the top portion **160** is detachably secured to the bottom portion **110**.

In reference to FIGS. 4, 4A, 5, 6, and 7, the rear side of the mobile electronic device **2** (such as a mobile electronic smart phone device **3**) is positioned planar against the front interior surface **114** of the body **112** of the bottom portion **110** of the case and a grip element **130** (to be described later in greater detail) of the bottom portion **110** is received through the window **166** of the top portion **160** of the case. The continuous lip **113a** of the bottom portion **110** is received and secured in the mating receptacle **164** of the top portion **160** via a snap-fit arrangement or mechanical interferential fit, thereby detachably securing the mobile electronic device **2** mesial the top portion **160** and the bottom portion **110**.

An annular membrane **168** is disposed along the continuous inner lip edge **167** of the window **166** on the bottom surface of the jacket **162** of the top portion **160**. The annular membrane **168**, such as an O-ring **169**, provides a water-impermeable seal about window **166** when the top portion **160** is detachably secured to the bottom portion **110**.

The body **112** is envisioned to further include button cusps (not shown in this particular embodiment) for receiving operational buttons of the mobile electronic device **2**, such as the power and volume buttons. Alternatively, it is further envisioned the body **112** may comprise removable panels or cut-out portions (also not shown), gains, and/or apertures **120** and button cusps. The cut-outs may be scored to facilitate quick, easy, and efficient removal thereof.

The body **112** further comprises a grip element **130** rigidly extending integrally, perpendicularly along an outer longitudinal side surface and outer bottom side surface of the continuous, peripheral sidewall **113** of the body **112**. In accordance to one embodiment, the grip element **130** may comprise a generally, crescent-shaped configuration comprising one or more loops **132** each of which forming finger through holes **134**. Preferably, grip element **130** comprises four loops **132** adjacently aligned and forming four finger through holes **134** sized for receiving user's index finger, middle finger, ring finger, and pinkie; user's thumb remaining free to navigate and operate the interface of the electronic mobile device **2** via the display screen **4** thereof.

In accordance to another embodiment, the grip element **130** is designed and configured in the form of a “brass knuckle-type” grip.

Referring now more particularly to FIG. 5A, in accordance to another embodiment, one or more distal phalanx braces **140** integrally project transversely from the outer surface **116** of the body **112**. Preferably a plurality of distal phalanx braces **140** integrally projects transversely from the outer surface **116** of the body **112**. Most preferably, the number of distal phalanx braces **140** are equal to the number of loops **132**, such as for example, a body **112** comprising

four loops 132 and four distal phalanx braces 140, as depicted in FIG. 5A. Each distal phalanx brace 140 comprises a protruding ridge 142 having a first side and a second side, the ridge 142 terminating upwardly into a curved crest from which the second side of the ridge 142 integrally extends downwardly to a fingertip receiver 144. The fingertip receiver 144 is a concavity slightly recessed below the outer surface 116 of the body 112. The crest may be horizontally-oriented, concave-shaped, or may be convex-shaped.

It is envisioned the body 112 of the bottom portion 110 may include one or more middle phalanx rests 150, in the form of minor recesses, wherein the middle phalanx rests 150 are disposed along the outer surface 116 of the body 112 adjacent the continuous, peripheral sidewall 113 and lower corner thereof supporting the grip element 130.

In accordance to still another alternate embodiment, the grip element is adapted and configured to be detachably secured to the protective cover body via a tether and coupling means or other means for facilitating detachable coupling of the grip element 30, 130 to the cover body.

In accordance to yet another embodiment, a protective cover for a portable electronic device is disclosed, wherein the cover comprises a generally planar body from which a continuous, peripheral sidewall extends integrally upward therefrom. The body includes a front or interior surface and a rear or outer surface. The body further comprises a grip element pivotally attached to an outer longitudinal side surface of the peripheral sidewall of the body via a pivot means. The pivot means is adapted to rotate the grip element about a specific angle of rotation or orientation. It is envisioned pivot means is adapted to articulate through approximately 180° of rotation and is further adapted and configured for being settable positionally in multiple fixed points along the 180° of rotation. More particularly, it is envisioned that the pivot means (and thus grip element) is adapted and configured for positioning about degrees of rotation selected from the group which includes, but is not limited to, approximately every 10°, 20°, 30°, and 45° of rotation, whether clockwise or counterclockwise in reference. In accordance to one embodiment, when pivotally rotated clockwise to 180°, the grip element is positioned coplanar to the rear surface of the body. When pivotally rotated counterclockwise from 180° to 0°, the grip element lies superjacent and parallel to the rear surface of the body in a fixed, overlapped position, thereby allowing the protective cover for a portable electronic device to be oriented in a compact configuration ("storage position") facilitating quick, easy, and efficient storage and transport thereof.

A retention mechanism is disclosed for removably retaining the grip element in the storage position. In accordance to one embodiment, the retention mechanism comprises a stem and a retainer, wherein the stem has a lower end integrally extending perpendicularly from the verso or rear surface of the grip element. A flange or lobe is integrally disposed at the upper end of stem.

The retainer comprises a base bifurcating into a pair of biased clamping members. The base integrally projects perpendicularly from the rear surface of the body. The clamping members define an arcuate or curved shape with distal ends. In a resting position, the clamping members are biased to exert a compressional force such that the distal ends of the clamping members are firmly engaged in contact forming a spaced cavity for receiving and retaining the lobe of the post in a removably secured manner. A force that would tend to push the lobe against the distal ends of the clamping members to a disengaged or unclamped position is

resisted by increased compressional biasing force of the clamping members. Thus, to removably retain the grip element in the storage position, the grip element is pivoted counterclockwise and engages the closed distal ends of the clamping members, and thereafter applying a degree of force suitable to allow the lobe to pass between the distal ends of the clamping members and into the spaced cavity thereof, thereby retaining the grip element in a removably secured manner. Other means suitable for detachably coupling the grip element superjacent and parallel to the rear surface of the body are envisioned, such as including, but not limited to, Velcro®, snap-fasteners, clip mechanisms, and the like.

In further accordance to the instant embodiment, the grip element comprises one or more loops each forming a finger through hole.

In still further accordance to the instant embodiment, the body may further comprise one or more distal phalanx braces integrally projecting transversely from the rear surface of the body. The distal phalanx braces are oriented such that upon positioning of the grip element in the storage position, the distal phalanx braces pass through the finger through holes of the loops.

Finally, in reference to FIGS. 8-8G, an ergonomic grip for a mobile electronic device 200, hereinafter "ergonomic grip 200", is disclosed. The ergonomic grip 200 comprises a planar plate 202 and a grip element 230, the grip element 230 is hingedly coupled to the planar plate 202. The planar plate 202 comprises a generally rectangular, planar configuration constructed of a lightweight, rigid or semi-rigid material, such as a plastic polymer, a thermoplastic, a metallic-plastic composite, or a durable rubber. The plate 202 further comprises an upper surface 204, a lower surface 206, and a continuous, beveled side edge 208 integrally joining the upper surface 204 and lower surface 206. The continuous, beveled side edge 208 comprises a top short side edge 208a opposing a bottom short side edge 208b and a left long side edge 208c opposing a right long side edge 208d. A knuckle 210 is integrally molded or securely attached superjacent the upper surface 204 of plate 202, intermediate and adjacent the left long side edge 208c of the continuous, beveled side edge 208. The knuckle 210 includes a central hole 211 defined longitudinally therethrough.

Referring now more particularly to FIGS. 8A and 8G, in order to securely attach the ergonomic grip 200 to a mobile electronic device 2, particularly a smart phone device 3, the lower surface 206 of the plate 202 of the grip 200 is attached superjacent the verso surface 3b of the smart phone device 3 or smart phone device 3 cover via a suitable adhesive 250.

Referring now to FIGS. 8-8G, the plate 202 further comprises a plurality of elements 220 upwardly projecting integrally from the upper surface 204 of the plate 202. The plurality of elements 220 is positioned in a centrally, linearly-aligned orientation atop the upper surface 204 of plate 202. The plurality of elements 220 each comprises a circular configuration defining a continuous, external peripheral sidewall 222 joined integrally to a generally, planar top wall 224. The planar top wall 224 defines an upper surface 225.

The grip element 230 is constructed of a lightweight, rigid or semi-rigid material selected from the group comprising a plastic polymer, a thermoplastic, a metallic-plastic composite, or a durable rubber. The grip element 230 comprises a body 231 comprising a pair of shoulders 232, namely, a first shoulder 234 and a second shoulder 235. The shoulders 234 and 235 integrally projecting outward, coplanar to the body 231 and aligned spatially parallel to one another forming a knuckle receiving cavity 240. The knuckle receiving cavity 240 is defined by the inner side edge 234a of first shoulder

234, the inner side edge 231a of the body 231, and the inner side edge 235a of second shoulder 235. The body 231 of grip element 230 includes an upper surface 231b opposing a lower surface 231c. The body 231 of grip element 230 further comprises at least one integrally molded annular loop 233, the at least one annular loop 233 forming at least one finger through hole 233a. Preferably, the body 231 of grip element 230 comprises a plurality of integrally molded annular loops 233, the plurality of integrally molded annular loops 233 being adjacently aligned and forming a plurality of finger through holes 233a. As depicted in FIGS. 8 and 8C-8E, grip element 230 is depicted with three annular loops 233. However, it is clearly envisioned grip element 230 may comprise less than or greater than three annular loops 233. Thus, the number of annular loops 233 illustrated in the figures is not intended to be limiting. Each of the plurality of annular loops 233 includes an inner circumferential sidewall 233b circumscribing the perimetric boundary of the finger through holes 233a, respectively. Each element 220 has a diameter D₂ measuring slightly less than the diameter D₁ of each finger through hole 233a. The annular loops 233 provide complementary element receptacles 233c.

The body 231 of grip element 230 defines a height H₁ equal to a height H₂ of the external peripheral sidewall 222 of each element 220.

Each of the pair of shoulders 232 includes a hole 238 and 239, respectively, defined coronally therethrough for receiving a pivot pin 242. The grip element 230 is adapted and configured for articulated pivotal rotation about the knuckle 210. The knuckle 210 is configured to allow grip element 230 to rotate thereabout to a selected angle of rotation or orientation and fixed at the selected angular orientation. The grip element 230 is hingedly coupled to the knuckle 210 of planar plate 202 via the pivot pin 242. Pivot pin 242 extends axially through the hole 238 of first shoulder 234, through the hole 211 of knuckle 210, and through the hole 239 of the second shoulder 235, thereby hingedly coupling grip element 230 to the planar plate 202.

In accordance to one embodiment, the knuckle 210 defines a polygonal cross-section comprising a plurality of flat external sides 212. For example, the knuckle 210 may comprise an elongated, polygonal shape selected from the group which includes, but is not limited to, a square, a pentagon, a hexagon, an octagon, a nonagon, and the like. In accordance with one exemplary knuckle 210 embodiment depicted in FIG. 8F, the knuckle 210 comprises an octagonal shape having eight flat external sides 212.

The grip element 230 pivotally rotates about the knuckle 210 and is fixedly settable along a plurality of positions through an angular rotation of approximately between 0° to 180°. When rotating or pivoting grip element 230 clockwise or counterclockwise, the inner side edge 231a of the body 231 of grip element 230 is positioned in flush contact with one of the plurality of flat external sides 212 of the knuckle 210, thereby fixedly setting the grip element 230 about the knuckle 210 in the selected angular position. A degree of force applied while pivoting the grip element 230 clockwise or counterclockwise disengages contact by the inner side edge 231a of body 231 with the flat external side 212 of knuckle 210, thereby allowing the user to pivotally adjust and fix the grip element 230 to a selectively-desired angular position about the knuckle 210.

In accordance to one embodiment, the grip element 230 is adapted and configured to be pivotally articulated and settable (or otherwise fixed) incrementally about degrees of rotation selected from the group which includes, but is not limited to, approximately 10°, 20°, 30°, 45°, 90°, 100°, 110°,

120°, 135°, and 180°, whether clockwise or counterclockwise in reference. In accordance to one embodiment, when pivotally rotated clockwise to 180°, the grip element 230 is positioned coplanar to the upper surface 204 of the planar plate 202.

In particular reference to FIG. 8E, the ergonomic grip 200 may be oriented in a flat, compact configuration or “storage position”, facilitating quick, easy, and efficient storage and transport thereof by the user, such as placement in user's 10 pocket or handbag. More particularly, as depicted in FIG. 8E, when pivotally rotated counterclockwise to 0°, the grip element 230 lies superjacent the upper surface 204 of the planar plate 202 in a fixed, superimposed position, the elements 220 received in corresponding element receptacles 233c in a snug-fit manner, and the upper surface 231b of the grip element 230 is coplanar to the upper surface 225 of each of the elements 220.

It is to be understood that the embodiments and claims are not limited in application to the details of construction and 20 arrangement of the components set forth in the description and/or illustrated in drawings. Rather, the description and/or the drawings provide examples of the embodiments envisioned, but the claims are not limited to any particular embodiment or a preferred embodiment disclosed and/or 25 identified in the specification. Any drawing figures that may be provided are for illustrative purposes only, and merely provide practical examples of the invention disclosed herein. Therefore, any drawing figures provided should not be 30 viewed as restricting the scope of the claims to what is depicted.

The embodiments and claims disclosed herein are further capable of other embodiments and of being practiced and carried out in various ways, including various combinations and sub-combinations of the features described above but 35 that may not have been explicitly disclosed in specific combinations and sub-combinations.

Accordingly, those skilled in the art will appreciate that the conception upon which the embodiments and claims are based may be readily utilized as a basis for the design of other structures, methods, and systems. In addition, it is to 40 be understood that the phraseology and terminology employed herein are for the purposes of description and should not be regarded as limiting the claims.

Furthermore, the purpose of the foregoing Abstract is to 45 enable the U. S. Patent and Trademark Office and the public generally, and especially including the practitioners in the art who are not familiar with patent and legal terms or phraseology, to determine quickly from a cursory inspection the nature and essence of the technical disclosure of the application. The Abstract is neither intended to define the claims of the application, nor is it intended to be limiting to the scope of the claims in any way. It is intended that the application is defined by the claims appended hereto.

What is claimed is:

1. An ergonomic grip for a mobile electronic device, the grip comprising:

a planar plate, the planar plate comprises:

a generally rectangular, planar configuration, an upper surface, a lower surface, and a continuous, beveled side edge integrally joining the upper surface and the lower surface, wherein the continuous, beveled side edge comprises a top short side edge opposing a bottom short side edge and a left long side edge opposing a right long side edge; and

a knuckle integrally molded or securely attached superjacent the upper surface of plate, intermediate

11

and adjacent the left long side edge, the knuckle includes a central hole defined longitudinally therethrough; and a grip element, the grip element is hingedly coupled to the planar plate, the grip element comprises a body having an upper surface opposing a lower surface, the body comprises a plurality of integrally molded annular loops adjacently aligned and forming a plurality of finger through holes, wherein the planar plate comprises a plurality of elements upwardly projecting integrally from the upper surface thereof, wherein the plurality of elements is positioned in a centrally, linearly-aligned orientation, wherein the plurality of annular loops provide complementary drum receptacles, the plurality of drums is received in corresponding drum receptacles in a snug-fit manner.

2. The grip of claim 1, wherein the body of the grip element further comprising a first shoulder and a second shoulder, the first shoulder and the second shoulder integrally project outward coplanar to the body and are aligned spatially parallel forming a knuckle receiving cavity.

12

3. The grip of claim 2, wherein the first shoulder includes a hole defined coronally therethrough and the second shoulder includes a hole defined coronally therethrough.

4. The grip of claim 2, further comprising a pivot pin, the pivot pin extends axially through the hole of the first shoulder, through the hole of the knuckle, and through the hole of the second shoulder, thereby hingedly coupling the grip element to the planar plate.

5. The grip of claim 1, wherein the grip element pivotally rotates about the knuckle and is fixedly settable selectively along a plurality of angular positions.

6. The grip of claim 5, wherein the grip element pivotally rotates about the knuckle and is fixedly settable selectively along a plurality of positions through an angular rotation of approximately between 0° to 180°.

7. The grip of claim 1, wherein the planar plate is constructed of a lightweight, rigid or semi-rigid material.

8. The grip of claim 1, wherein the grip element is constructed of a lightweight, rigid or semi-rigid material.
